SPOT-WELD EDGE GAUGE

Bernard Gross and Leo W. Cornwall, San Diego,
Calif., assignors to Rohr Aircraft Corporation,
Chula Vista, Calif., a corporation of California

Application November 21, 1945, Serial No. 629,948

6 Claims. (Cl. 219—4)

1

Our invention relates to spotweld edge gauges, and its objects are to provide a mechanical means for guiding the formation of a line of spotwelds at a uniform distance from one of the edges of the sheets of material which are being welded together by a conventional spotwelding machine; to adjust and adapt such guiding means for use with electrodes long or short of varying lengths, and to furnish means for readily turning out of the way for the time being such guiding means when its use is not required. Other objects will appear from the drawings and as hereinafter set forth and described.

In the process of spotwelding as heretofore generally carried on, it has been found difficult by the workman, particularly at high speeds, to form and maintain a line or sequence of spotwelds equidistant from the edge of the welded work as is required by many working drawings. This is because the workman depending entirely upon the eye to judge such distance and to apply the welds is unable to secure accurate and uniform results. It is by reason of this situation, and to meet this problem that we have conceived and developed our invention, resulting in the production of a gauge which is the subject matter of this application, and which fully secures and maintains the uniformity and accuracy desired.

Attention is hereby directed to the drawings, illustrating a preferred form of our invention, in which similar numerals of designation refer to similar parts throughout the several views, and in which—

Figure 1 is a side elevation of our spotweld edge gauge, showing it attached to the lower electrode holder of a conventional spotwelding machine, and the roller of said gauge in contact with the edge of the two sheet welded material;

Fig. 2 is a plan view of the gauge and electrode holder shown in Fig. 1 with the contact roller and welded material removed;

Fig. 3 is a section on line 3—3 of Fig. 1, looking in the direction of the arrows;

Fig. 4 is a section partly in end elevation on line 4—4 of Fig. 2, with the roller restored looking in the direction of the arrows;

Fig. 5 is a section on line 5—5 of Fig. 1, looking in the direction of the arrows, and

Fig. 6 is a section on line 6—6 of Fig. 4, looking in the direction of the arrows.

Referring to the drawings, our invention comprises a rod 7 and an edging roller assembly and carriage 8 therefor, slidably mounted upon said rod, the inner end of said rod having a split sleeve 9, shaped to make contact with the lower elec-

2

trode holder of a conventional spot welding machine, and to be firmly secured to said electrode holder by the thumb screw 10 in threaded engagement with ears 11 integral with said sleeve, 5 adjacent to and separated by the split therein. Preferably extending over one side of the middle and outer portions of the rod are the regularly disposed teeth or notches 12, the purpose of which will shortly be disclosed. Included in said carriage, is the sleeve 14 enclosing the rod 7 and longitudinally slidable thereon; the elongated key 1a affixed to the under side of said rod and engaging with the keyway 15 in the adjacent wall of said sleeve serving to prevent rotation of said sleeve 14 while at the same time permitting the same to be slid along such rod; and the stop pin 13 affixed to the outer end of said rod preventing said sleeve from sliding off the same. Rotatably mounted upon said sleeve 14, between the rim 53 10 thereof and clevis 29 thereon, is the open-ended box 36, having a barrel shaped bottom 16 in sliding contact with said sleeve, upright sides 17 and 18, and a top 19 secured to said sides by pins or set screws 20; the said top having integral therewith and extending inwardly therefrom, the round rod 21, upon which is pivotally mounted one end of the bracket 22; a screw 23 in threaded engagement with an opening in the wall of said bracket and extending therethrough and contacting with said rod, serving normally to prevent said bracket from rotation. Upwardly extending from the other end of said bracket 22 and firmly secured thereto is the bolt 52, upon which is rotatably mounted the roller 24, having the inner metallic sleeve 24a, fibre insulation layer 25, and steel outer jacket or cover 26.

In order to move the roller 24 nearer to or farther away from the electrode 27, I preferably secure by means of screws 28, in an annular recess provided therefor in the outer end of the sleeve 14, the clevis 29, to the walls of which is pivotally secured by the pin 30 within opening thereof the ratchet lever 31, having the inner face of its head 32 provided with serrations shaped to engage with the teeth 12 of the rod 7, and having a stud on its arm 33 engaging with an expansion spring 34 connected by a stud 37 with a lip 35 integral with the sleeve 14; said spring operating normally to keep the serrations of head 32 in spring yielding engagement with the teeth of said rod.

When it is desired to adjust the roller for use with a shorter electrode the shank of which does not reach above the plane of the lower end of said roller and is a little below such plane, the

screw 23 may be loosened, and the roller 24 inverted and turned 180 degrees from an upright to a downwardly depending position, and said screw 23 again tightened. When in such position, and when the sheets 38 and 39 to be welded are in position on top of the lower electrode, the roller 24 may be moved into the desired contact with the edges of said sheets.

For the purpose of temporarily moving the roller 24 out of the way of the operator when it becomes necessary or desirable to weld without the use of our improved gauge, and without detaching the same, we preferably install in the space 40 between the upright sides 17 and 18 of the box 36, the body 41 of the lever 42, pivotally mounted upon the pin 43 extending through the sides of said box; the protruding outer arm of said lever acting as a handle 44, and the inclosed inner arm 45 having a downwardly depending tongue 46 shaped and positioned normally to engage with the opening 47 extending through the upper walls of the barrel 16 and the sleeve 14. An expansion spring 48 engaging with a stud 49 on the ear 50 integral with the enclosed end of lever 42 and also engaging with a stud 51 embedded in the underside of top 19, serves to keep the tongue 46 in spring yielding engagement with the opening 47. Upon the handle 44 being manually depressed and the arm 45 caused to move upwardly, the tongue 46 will be lifted out of engagement with the opening 47, and the entire box 36 as a whole carrying the roller 24 and adjacent parts may be turned downwardly out of the way, without disturbing the ratchet lever 31 and its engagement with the teeth 12 on rod 7, and without disturbing the longitudinal adjustment of roller 24 in respect to the electrode 27. Later, as is obvious, the box 36 may be quickly rotated back its original position and again locked therein through reengagement of the tongue 46 with the opening 47.

Preferably, the material of all the parts of our improved gauge should be of non-magnetic conducting materials in order that the magnetic flux or field induced around the electrode during welding will not interfere or affect the movement of such parts while serving the purposes of our invention.

Our invention may be embodied in other specific forms without departing from the spirit or essential characteristics thereof. The present embodiment, as above set forth, is therefore to be considered in all respects as illustrative and not restrictive, the scope of our invention being indicated by the appended claims rather than by the above description, and all changes which come within the meaning and range of equivalency of the claims are therefore intended to be embraced therein.

What we claim and desire to secure Letters Patent is:

1. A spotweld edge gauge, comprising a rod, means for securing one end of said rod to a spotwelding machine adjacent to one of the electrodes thereof, an edging roller assembly and carriage therefor mounted upon said rod to slide

thereon toward and from said electrode, and means for detachably clamping said assembly to said rod in adjusted position thereon.

2. A spotweld edge gauge, comprising a rod, means for securing one end of said rod to the lower electrode holder of a spot welding machine, an edging roller assembly and carriage therefor mounted upon said rod to slide toward and from said holder, and means for clamping said assembly to said rod in adjusted position thereon.

3. A spotweld edge gauge, comprising a rod, means for securing one end of said rod to a spotwelding machine adjacent to one of the electrodes thereof, a carriage mounted upon said rod to slide toward and from said electrode, an edging roller mounted upon said carriage and positioned to be moved to abut against edges of the material to be welded when in contact with said electrode, and means for clamping said carriage to said rod to secure adjustment of said roller in respect to the edges of said material.

4. A spotweld edge gauge, comprising a rod having serrations extending along one side thereof, means for securing one end of said rod to the lower electrode holder of a spotweld machine, a carriage mounted upon said rod to slide toward and from said holder, an edging roller mounted upon said carriage and positioned to be moved to abut against the edges of the material to be welded and resting upon the electrode of said holder, and ratchet means mounted upon said carriage for contacting said serrations and clamping said carriage to said rod to secure adjustment of said roller in respect to the edges of said material.

5. A spotweld edge gauge, comprising a rod, means for clamping one end of said rod to the lower electrode holder of a spotweld machine, a carriage pivotally mounted upon said rod to slide toward and from the electrode of said holder, an edging roller mounted upon said carriage and positioned to be moved to abut against the edges of material to be welded and resting upon said electrode, means connected with said carriage for locking the same in upright position on said rod and permitting said carriage when unlocked to be inverted thereon, and means for clamping said carriage to said rod to secure adjustment of said roller in respect to the edges of said material.

6. A spotweld edge gauge, comprising a rod, means for clamping one end of said rod to the lower electrode holder of a spotweld machine, a carriage mounted upon said rod to slide toward and from the electrode of said holder, an edging roller pivotally mounted upon said carriage so to move from an upright to an inverted position and to be adjusted while in one of such positions to abut against the edges of the material to be welded and resting upon said electrode, and means for clamping said carriage to said rod when in adjusted position in respect to said electrode.
